UNITED STATES PATENT OFFICE.

CHARLES DUNCANSON YOUNG, OF COLUMBUS, OHIO.

SWING-MOTION TRUCK FOR CARS.

944,165.

Specification of Letters Patent. Patented Dec. 21, 1909.

Application filed August 6, 1909. Serial No. 511,634.

To all whom it may concern:

Be it known that I, CHARLES D. YOUNG, of Columbus, in the county of Franklin and State of Ohio, have invented certain new and useful Improvements in Swing-Motion Trucks for Cars; and I do hereby declare the following to be a full, clear, and exact description of the invention, such as will enable others skilled in the art to which it appertains to make and use the same.

My invention relates to an improvement in swing motion trucks for cars, the object being to provide a truck of this character in which provision is made for proper strength and for safety in the event of the breakage of any of the parts from which the bolster is suspended.

A further object is to provide a construction, whereby in the event of breakage of any of the bolster suspending parts, the said parts will become locked within the side frames, thus making the truck safe for continued service.

With these and other objects in view, my invention consists in the parts and combination of parts as will be more fully described and pointed out in the claims.

In the accompanying drawings, Figure 1 is a view in side elevation of a truck, some of the concealed parts being shown in dotted lines; Fig. 2 is a top or plan view of one half a truck; Fig. 3 is a view in end elevation of same; Fig. 4 is a section on line A—B of Fig. 1; Fig. 5 is a section on the line C—D; Fig. 6 is a section on the line G—H, and Fig. 7 is a view in section on the line E—F.

1 represents the side frame of the truck composed of an upper arch 2, a lower arch 3, parallel vertical columns 4 and 4^a, journal boxes 5, and journal box tie bar 6 all the above parts except the journal boxes and the tie bar being cast integral.

Formed in the frame between the upper and lower arches and the columns 4, is the bolster opening. The bolster is supported at its ends within the openings in the two side frames, upon the springs 11, carried by the spring seats 8, the latter being mounted upon the lower member of the hanger yokes 9, the vertical members of which are suspended from their upper ends on two pins 10, as clearly shown in Fig. 5.

The pins 10, two for each upright member of each yoke, pass through elongated slots located on opposite sides of the center

of said member as clearly shown in Fig. 5, so that normally, the yoke is suspended from all four pins, consequently cannot swing except when the truck tilts, as in turning a curve, or when forcibly swung by the endwise movement of the bolster.

The upper face of the lower or horizontal member of the yoke, is curved in the arc of a circle, and forms a support for the spring seat 8, which latter is enlarged on its under face at its center, which enlargement is provided with a concave recess conforming in shape and size to the convex face of the horizontal member of the yoke. This spring seat is a box like structure open at its top and provided at its front and rear with upwardly projecting integral members 6, forming in effect columns which latter are embraced or overlapped by the guides 7 secured to the bolster, and operate to guide the latter in its vertical movements. As the spring seat is mounted to rock on the yoke, and as the bolster guides embrace the upwardly projecting members 6 of the spring seat, it follows that any endwise movement of the bolster will be transmitted to the spring seat and either rock the latter on the yoke or cause the yoke to swing.

One important feature of my invention is the construction of the lower arch, and from an inspection of Figs. 4 and 5, it will be seen that the contour of the upper face thereof is formed by striking arcs from the centers of the two pins 11 on which each upright member of the yoke is journaled, the two curved surfaces forming in effect a pocket in which the lower member of the yoke moves. By reason of the two supporting pins for each upright member of the yoke, the path of movement of the spring seat 8 and yoke 9 in swinging, is concentric with the curved surfaces of the pocket, and owing to the shape of the lower arch, the size of the yokes, and the proximity of the lower member of the latter to the pocket in the lower arch, it is apparent that if one or more pins 10, or the yoke should break, the latter would fall into the pocket and thus sustain the parts in position for safe service.

If one pin should break, or the yoke be ruptured and disengaged from one pin the weight will be transferred to the other pin and thus changing the center of gravity of the yoke, and swinging its lower end sideways and into contact with the lower arch. The parts are then locked and rigid. The

truck under these conditions becomes of the rigid type, and is safe for operation, in that it will be impossible for the bolster 7 to disengage itself from side frame 1, on account 5 of the shape of the carrying arch 3, and the construction of the engaging surfaces of the spring seat and yoke. Any breakage that would let the lower member of the yoke down onto the lower arch, would also lower 10 construction of the engaging surfaces of the spring seat onto the arch and thus support the spring seat solidly on the arch.

The cylindrical bearing of the spring seat on the horizontal member of the yoke, as 15 shown at *j* in Fig. 4, is of ample area to reduce the wear of parts 8 and 9 to a minimum and bring the lowest point of swinging for hanger yoke 9 contiguous to lower arch 3.

While I have shown a hanger with two 20 pin supports at each side, I do not confine my invention to such construction, as the form of arches may be made to conform to any method of supporting, such as one pin center hung, or one pin to the right or left 25 of center.

The center pins are of reduced diameters at their centers as shown in Fig. 7, hence when the yokes are swung from the central reduced portion, the pins are securely locked 30 in place.

Each side frame 1 is provided with openings at points as close as possible to the point of loading, to receive the ends of the cross ties 12, which latter are pivotally secured 35 to the side frames, on opposite sides of the bolster by pins 13 as shown in Fig. 2. By this arrangement I provide for flexibility between the side frames and cross ties without affecting the parallelism of the side 40 frames.

Both cross ties 12, are provided with integral brackets *d* for the attachment of the brake beam hangers, and for the brake beam safety guard or release spring *h*, and one is 45 provided with the seat *e* for the attachment of the live brake lever guide 12^a, and the other with a seat *f* for the attachment of the dead lever support 12^b.

It is evident that many slight changes 50 might be resorted to in the relative arrangement of parts shown and described without departing from the spirit and scope of my invention hence I would have it understood that I do not wish to confine myself to the exact construction and arrangement of parts shown, but,

Having fully described my invention what I claim as new and desire to secure by Letters-Patent, is:—

60 1. In a swing motion truck the combination with a truck frame, having a bolster opening therein, the lower wall of the bolster opening having a recess or pocket in its upper face, of a swinging yoke journaled

within the bolster opening above said recess 65 or pocket and a bolster carried by said yoke.

2. In a swing motion truck the combination with a side frame having a bolster opening therein, the lower wall of said opening having a recess or pocket therein, 70 of a yoke journaled to the frame, a spring seat mounted on the yoke, springs carried by said seat and a bolster mounted at one end on the springs.

3. In a swing motion truck the combination 75 with a side frame comprising upper and lower arches and columns, the lower arch being provided on its upper face between the columns with a depression or pocket to receive the yoke in the event of 80 breakage of any of the suspending parts, of a spring seat journaled on the yoke, and a bolster carried by said springs.

4. In a swing motion truck the combination 85 with a side frame having a bolster opening and a pocket at the base of said opening, of a yoke pivoted to the frame and suspended in a plane above the pocket, a spring seat journaled on the yoke and provided with upstanding members, springs on 90 said seat, and a bolster seated on the springs and provided with guides embracing the upstanding members of the spring seat.

5. In a swing motion truck the combination 95 with a side frame having a bolster opening, of a yoke mounted to swing in said opening, a spring seat carried by said yoke and having upwardly projecting members, springs on said seat and a bolster having guide flanges embracing the upwardly projecting 100 members of the spring seat.

6. In a swing motion car truck the combination with a side frame, a yoke pivoted thereto and a bolster, of a spring seat mounted on the yoke and having members 105 rigid with the seat engaged by the bolster.

7. In a swing motion truck the combination with a side frame composed of upper and lower arches and columns, the upper face of the lower arch being concaved, of a 110 yoke each upright member of which is provided with two elongated slots, pins passing through said slots and carried by the columns, each pin supporting said yoke concentric with one side of the concavity in the 115 lower arch and eccentric to the other side, and a bolster supported on said yoke.

8. In a swing motion truck, the combination with a side frame having a bolster opening, a hanger yoke pivotally connected 120 to said frame near the upper end of said opening and a bolster carried at one end by the yoke, of cross ties secured at their ends within openings formed in the side frame between the columns and journal boxes and 125 approximately in the horizontal plane of the pivotal supports for the hanger yoke.

9. In a swing motion truck, the combina-

tion of a side frame provided with openings immediately adjacent the load carrying points, cross ties and means for flexibly connecting the cross ties at their ends within said openings.

10. In a swing motion truck, the combination of a side frame provided with openings immediately adjacent the load carrying points, cross ties having vertical openings in their ends, and pins flexibly connecting said ties to the side frame.

11. A cross tie for rail road trucks provided with integral supporting lugs respectively for the brake beam hangers, lever guide and release spring.

In testimony whereof, I have signed this specification in the presence of two subscribing witnesses.

CHARLES DUNCANSON YOUNG.
